UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL DISTRIBUTING MACHINE.

Application filed January 4, 1928. Serial No. 244,389.

This invention relates to typographical distributing machines, such as Linotype machines of the general organization represented in Letters Patent of the United States 5 to O. Mergenthaler, No. 436,532, wherein circulating matrices are released from a magazine in the order in which their characters are to appear in print and then assembled in line, the composed line transferred to the face of a slotted mold, the mold filled with molten metal to form a slug or Linotype against the matrices which produce the type characters thereon, and the matrices thereafter returned through distributing 10 mechanism to the magazine from which they started. More particularly, it relates to that class of machines (such as represented in my former Patent No. 1,397,974) designed to handle matrix fonts which differ from one 15 another in the size and number of characters. These fonts, for example, may be the ordinary or ninety character fonts used exclusively for the composition of "straight" matter, and the special seventy-two or fifty-five 20 character fonts used for the composition of head letter or display matter.

In machines of the above class, it has been found desirable to make use of two interchangeable magazine entrances and two interchangeable distributor bars in distributing 25 matrices of the ordinary and display fonts, the tooth combinations of one distributor bar and the partitions of the corresponding entrance being equally spaced apart for handling the ordinary ninety character fonts, and the tooth combinations and partitions of the other bar and entrance being unequally spaced for handling the larger seventy-two character fonts.

The present invention contemplates certain improvements in this type of distributing mechanism which, while capable of more general application, are particularly adapted to the machine disclosed in my prior Patent 45 No. 1,570,258, wherein the magazine entrances are arranged back to back in inverted relation to each other and rotatably mounted on the same axis so as to be reversible at will for interchange. In the preferred embodiment illustrated, the two distributor bars, which are movably arranged in a novel fashion, are operatively connected to the hand lever employed for rotating the entrances in such manner that either distributor bar and the corresponding magazine en- 50 trance may be brought into operative position simultaneously by the same operation. Other improvements, including means for designating the entrance and bar in use, are also provided and will best be understood from the detailed description to follow.

Referring to the drawings:

Fig. 1 is a side elevation, partly in section, of the upper part of a Linotype machine equipped with the present improvements;

Fig. 2 is a view similar to Fig. 1 showing the parts in different relative positions during the interchange of the entrances and the distributor bars;

Fig. 3 is a front view of the parts shown in Fig. 1;

Fig. 4 is a detail horizontal section taken on the line 4—4 of Fig. 3;

Fig. 5 is a view similar to Fig. 1 showing the means whereby the entrance frame is supported when it is swung downwardly for access to the magazines;

Fig. 6 is a detail perspective view of the said entrance supporting means; and

Figs. 7 and 8 are detail diagrammatic views of the two distributor bars and associated entrances, showing the relative spacing of the tooth combinations and entrance partitions.

The several magazines are carried by a shift frame A, which is arranged to be raised and lowered to bring any one of the selected magazines into operative relation to the assembling and distributing devices. As herein illustrated, the shift frame A carries two standard magazines A² and a single magazine A¹, the magazine A² being provided with ninety one grooved channels spaced apart in the usual way to adapt them to contain the matrix columns of the ordinary ninety character fonts, and the magazine A¹ being provided with only seventy three grooved channels spaced apart in a different manner to adapt them to contain the matrix columns of the seventy two character display fonts. When either of the magazines A² is in operative position, the regular magazine entrance B is employed to deliver the matrices thereto from the distributing mechanism, and when the magazine A¹ occupies such operative position, the special magazine entrance C is so employed. The entrances differ in the number and spacing of their partition plates so that the entrance B will present ninety one channels for coopera- 110

tion with the magazines A² and the entrance C seventy three channels for cooperation with the magazine A¹.

As in my prior Patent No. 1,570,258 hereinbefore mentioned, the entrances B and C are arranged in inverted relation to each other, their supporting frames D being fastened together so as to constitute a reversible holder or support which is rotatably mounted, by means of trunnions D¹ secured to its opposite ends, in the upright side members of a rocking frame E. The frame E is pivotally mounted at E¹ in the fixed right and left hand brackets O¹ and is normally held in operative position against a stop O² by a pull spring E² anchored to the main distributor frame O and indicated by dotted lines, Fig. 1. It will be noted (see also Fig. 5) that the right hand bracket O¹ is provided with a depending arm O³ formed at its lower end with a pocket O⁴, the purpose of which will hereinafter be explained. As thus arranged, the pivoted frame E may be swung back and forth at will to move the entrance in use into and out of operative position and at the same time permit rotation of the entrance holder.

Normally the entrance holder is locked against rotation by a spring latch F slidably mounted within a plate F¹ secured to the frame E, and adapted to engage one or the other of a pair of notches d formed in the opposite ends of a rotating block D², the latter being fastened to one of the trunnions D¹ which projects through its bearing in the frame E. When a change of entrances is desired, the latch F is withdrawn to release the holder and the latter given a half-turn (180°) which is sufficient to interchange the entrances in position with each other. In order that these latter operations may be effected automatically as the frame E is rocked about its pivotal axis, two cam plates O⁵, O⁶ are provided which are fastened to the fixed bracket O¹ and arranged to cooperate with the releasing pin f of the latch and with a pair of studs D³ protruding from the outer side face of the rotating block D². The form and arrangement of the cam plates O⁵, O⁶ are such that it is merely necessary to swing the frame E downwardly a limited distance from and then forwardly to its normal position in order to bring one entrance or the other into operative position. The rocking of the frame E is effected from the front of the machine by means of a conveniently located hand lever G which is journaled on a fixed pivot G¹ and connected to said frame by a link G² through an upright arm E³.

The foregoing parts, their construction and mode of operation are fully set forth in aforesaid Patent No. 1,570,258, to which reference may be had if desired.

66 The distributor proper comprises two dis-

tinct distributor bars B¹, C¹ and a common set of matrix conveying screws H. The bar B¹ is provided with ninety one tooth combinations b which are equally spaced apart to correspond to the spacing of the matrix channels in the magazine entrance B and each magazine A², and the bar C¹ is provided with only seventy three combinations c unequally spaced apart to correspond to the spacing of the channels in the magazine entrance C and the special magazine A¹ (see Figs. 7 and 8).

According to one feature of this invention, these bars are pivotally mounted so that either may be rocked into operative relation to the conveying screws H, being provided respectively at their opposite ends with bracket plates B², C² which are journaled on the reduced end portions of the two upper conveying screws H. Each distributor bar is connected by a curved link J¹ to an overlying horizontal bar J which is slidably mounted in a suitable guideway J² fastened by screws and dowels j (Fig. 4) to a fixed bracket J³, the latter being secured to the crossbar of the main distributor frame O and formed with a pair of forwardly projecting arms J⁴. As will be seen, the arrangement is such that by sliding the bar J to and fro, the distributor bars B¹, C¹ will be rocked alternately into and out of operative position.

According to another feature of the invention, it is proposed to effect the interchange of the distributor bars simultaneously with the interchange of the magazine entrances B, C and by the same operation. To this end, means controlled by the hand lever G are provided for operating the sliding bar J. Such means (as best shown in Figs. 1, 2 and 3) consist of a short rock shaft K journaled in the bracket arms J⁴ and provided with a pair of crank arms K¹, K² disposed at right angles to each other, the arm K¹ extending downwardly from the shaft K to make connection with the bar J and the arm K² being pivotally connected at its upper end to a vertically disposed link member K³. The link member K³ is suspended from the arm K² and is guided in a groove o formed in a bracket O⁷ secured to the front side of the main frame O. At its lower end, the said link member is provided with a stud k by which it may be raised and lowered to move the bar J to and fro through the connections just described. In the present instance, the link member K³ is operated by means of a latch bar G⁵ slidably mounted for longitudinal movement on the inner face of the hand lever G, a pull spring G⁴ being employed to hold said bar in its retracted position. A pin G⁶, projecting laterally from the forward end of the bar G⁵ through a slot in the lever G, is also provided and arranged in juxtaposition to the handle G⁶.

of the lever G, so that the latch bar may be pulled forwardly against the tension of the spring G⁴ as the handle G⁶ is grasped by the operator. Near its rear end, the bar G³ is formed with a forked portion G⁷ which is located in the same vertical plane as the stud k on the lower end of the link K³ but which is arranged to normally clear said stud when the hand lever is rocked about the pivot G¹.

Assuming the parts to be in the position shown in Fig. 1, with the regular magazine entrance B and distributor bar B¹ in use, and a change of entrances and distributor bars is required to cooperate with the display magazine A¹ (which according to the showing of Fig. 1 has already been brought into operative position), it will now be seen that by raising the hand lever G until the entrance supporting frame E is swung to its lowermost position as shown in Fig. 2, the forked portion G⁷ of the latch bar G³ will be located in operative relation to the stud k, so that, by grasping both the pin G⁵ and the handle G⁶, the lever G may be temporarily connected with the link member K³. Consequently, as the lever is lowered to rock the entrance frame upwardly, the link K³ at the same time is drawn downwardly and, through the rock shaft K, will slide the bar J toward the rear to swing the distributor bars clockwise upon their respective axes. When the hand lever has reached the limit of its downward stroke and been released, the parts will be caused to assume their relative positions indicated by the dotted lines in Fig. 2, the magazine entrance C and the distributor bar C¹ occupying their respective operative positions to handle matrices of the special display fonts. To again reverse the positions of the bars and entrances, however, the connection between the hand lever G and link K³ is first established by drawing the latch bar G³ forwardly before operating the hand lever but is broken later by releasing the latch bar when the lever has reached the limit of its upward stroke, the return movement of the lever at such times being devoted solely to the restoration of the magazine entrance B to its original position. It will be observed (see Figs. 1 and 3) that the link K³ is also provided with an adjustable banking screw k¹ projecting from its rear edge and which is adapted to engage the lower position of the link to engage the bottom of the groove o and thus sustain the link K³ so as to locate the stud k in operative relation to the latch bar G³.

In carrying out the invention, it is further proposed to indicate to the operator the particular entrance and distributor bar which are at the time in use and thus avoid the difficulties arising through an improper change which might cause an entrance and bar that do not correspond to the magazine

to be brought into operative position. For this purpose, see Figs. 2 and 3, two indicator plates c¹, c² are fastened respectively against the top edge and one side face of the distributor bar C¹, the latter being in front of the bar B¹ and in view of the operator. The plate c¹ is stamped "90" to indicate the ninety character font and is displayed when the bar B¹ is in operative position, and the plate c² is stamped "72" to indicate the special seventy two character font, being displayed when the bar C¹ occupies said operative position.

An indicating device is also employed which serves in like capacity for the magazine entrances B, C. This device (as best shown in Figs. 1 and 2) is self-contained in a small bracket P secured to the main frame O, and comprises a horizontally disposed slide rod P¹ resiliently mounted in the bracket and loosely connected to one arm of a small bell crank lever P². The other arm of said lever is operatively connected by a link P³ to a small vertically movable plate P⁴ stamped "72", "90" and mounted to slide upon the rear face of a flange P⁵ forming part of the bracket P. A slotted keeper piece P⁶ retains the plate P⁴ in operative position, and an aperture P⁷ formed in the flange P⁵ enables one or the other of the said markings to be displayed according to the position of the plate P⁴ and the actuating rod P¹ to which it is connected. That is to say, when the rod P¹ is pushed forwardly, the plate P⁴ is raised to expose the marking "90" through the aperture P⁷ (Fig. 1) and when it is moved in the opposite direction, the plate is lowered to expose the marking "72" (Fig. 2). In the present embodiment, the operation of the rod P¹ is controlled by an adjustable screw stud d¹ projecting laterally from one side of the entrance rotating block D² and which is adapted to engage the rear end of said rod and push it forwardly when the frame E is rocked upwardly to locate the entrance B in operative position (Fig. 1). When the frame E is rocked downwardly, however, to reverse the entrances, a compression spring P⁸ surrounding the rod presses the latter to the rear as far as the pin and slot arrangement P⁹ permits (see Fig. 2). A reversal of the entrances causes the opposite side of the rotating block to be opposed to the rod P¹ so that, when the entrance C has been brought into operative position as indicated by the dotted lines (Fig. 2), the relation of the parts is such that the block will clear or stop short of the rear end of said rod and leave it undisturbed. As a result of this arrangement, when the magazine entrance B and distributor bar B¹ are in operative position to handle the ordinary fonts, the indicator plate c¹ which is fastened to the top of the bar C¹ and marked "90" will be dis-

played and the plate P^4 will occupy its raised position to expose the corresponding "90" marking. Conversely, when the entrance C and bar C^1 are in use, the indicator plate c^2 marked "72" and fastened to the side of the bar C^1 will be displayed and the like marking on plate P^4 , which at such times occupies its lower position, will be exposed.

Another feature of the invention resides in the provision of means which are also particularly adapted to the present type of distributing mechanism and are intended to prevent the accidental unlocking of the magazine entrances when the rocking frame E is swung downwardly for access to the magazines. Heretofore, extreme care has had to be observed on such occasions so as to avoid lowering the frame E from the rear far enough to cause the automatic release of the entrances and the consequent rotation thereof about their pivotal axes. To overcome these difficulties, there is provided a bail-shaped finger bar R disposed longitudinally of the frame E and arranged conveniently near the rear edge thereof, the side arms R^1, R^2 of the bar being hingedly connected at their free ends to the respective right and left hand side members of said frame. A strut R^3 depending from the arm R^1 between a pair of stop pins e, e^1 constitutes a part of the finger bar and by means of the said stop pins limits its pivotal movement in both directions. Normally the strut R^3 is held rearward against the stop pin e by a light pull spring R^4 , which thus maintains the finger bar proper resiliently in position slightly above the rear edge of the frame E . Strut R^3 is intended primarily to support the frame E and the parts connected thereto when the latter is lowered directly by hand from the rear of the machine, and for this reason, it is provided at its lower end with a stud R^5 which is adapted to clear the bracket arm O^3 hereinbefore mentioned when the frame is rocked downwardly by means of the hand lever G . At other times, however, (usually when access to the magazines is desired), the finger bar R is pressed down (see Fig. 5) so as to rock the strut R^3 against the stop pin e^1 . The stud R^5 is thus moved forwardly into a position where it will engage the pocket O^4 in the arm O^3 when the frame is lowered, the relation of the parts being such that the frame will be arrested by the stud in the dotted line position indicated in Fig. 5 before the latch F has been completely withdrawn from the rotating block D^2 .

As before stated, the present improvements have been shown merely in preferred form and by way of example and as applied to a particular kind of machine, but obviously many modifications and alterations therein and in their mode of adaptation will readily suggest themselves to those skilled

in the art and still be comprised within the scope of the invention.

Having thus described my invention, its construction and mode of operation, what I claim and desire to secure by Letters Patent of the United States, is as follows:

1. In a typographical distributing machine, the combination of two magazine entrances arranged permanently in inverted relation to each other and movably mounted so as to be interchangeable in operative position with each other, two distributor bars also movably mounted so as to be interchangeable in operative position with each other, and means operable to effect the interchange of the magazine entrances and the distributor bars simultaneously. 75

2. In a typographical distributing machine, the combination of two rotatable magazine entrances differing as to form and 80 arranged permanently in inverted relation to each other, two distributor bars also differing as to form to correspond with the respective magazine entrances and pivotally mounted so that either may be brought into operative position, and unitary means operable at will whereby either bar and the corresponding entrance are brought into action simultaneously. 90

3. In a typographical distributing machine, the combination of two magazine entrances movably mounted and arranged in inverted relation to each other; two distributor bars also movably mounted so as to be interchangeable in operative position with each other, means operable at will to reverse the position of the entrances, and subsidiary means operable by said reversing means for effecting the interchange of the distributor bars. 95 100

4. In a typographical distributing machine, the combination of two magazine entrances arranged in inverted relation to each other, a reversible holder or support therefor, a pivoted frame in which said holder 110 is rotatably mounted, a hand lever operable from the front of the machine and connected to the pivoted frame for rocking it about its pivotal axis, means controlled by the rocking movement of said frame for reversing the position of the rotatable holder to bring either magazine entrance into use, two distributor bars pivotally mounted so as to be interchangeable in operative position with each other, and subsidiary means operable by the hand lever for effecting the interchange of the distributor bars. 115 120

5. Typographical distributing mechanism including, in combination, a set of matrix conveying devices and two independently supported distributor bars arranged at right angles to each other and pivotally mounted so that either may be brought into operative relation to said devices. 125

6. Typographical distributing mechanism 130

including, in combination, a set of matrix conveying devices, two distributor bars arranged at right angles to each other, and a reciprocating slide connected to the bars and 5 operable to locate either one in operative relation to said devices.

7. In a typographical distributing machine, the combination of two magazine entrances movably mounted so as to be interchangeable in position with each other, two distributor bars also movably mounted so as to be interchangeable in operative position with each other, means for effecting the interchange of the entrances and the distributor bars simultaneously, and means visible from the front of the machine for designating the particular bar and entrance in use.

8. Typographical distributing mechanism including, in combination, two magazine entrances movably mounted so as to be interchangeable in operative position with each other, and an indicator, operable automatically as the entrances are interchanged, 25 for designating the entrance in use.

9. Typographical distributing mechanism including, in combination, two magazine entrances arranged in inverted relation to each other, a pivoted frame in which they are 30 rotatably mounted for interchange, and an indicator, operable automatically as said frame is rocked about its pivotal axis, for designating the entrance in use.

10. In a typographical distributing machine, the combination of two magazine entrances arranged in inverted relation to each other, a reversible holder or support therefor, means operable from the front of the machine for reversing the support to bring one 40 or the other of the entrances into operative position, and an indicator operable automatically as the support is reversed to designate the entrance in use.

11. In a typographical distributing machine, the combination of two magazine entrances arranged in inverted relation to each other, a pivoted frame in which they are rotatably mounted so as to be interchangeable in position with each other, 45 releasable means controlled by the rocking of the frame about its pivotal axis for locking the entrances in either of their reversed positions, and subsidiary means operable at will to prevent unlocking of the entrances 55 when the frame is rocked downwardly for access to the magazines.

12. In a typographical distributing ma-

chine, the combination of two magazine entrances arranged in inverted relation to each other, a frame in which they are rotatably mounted so as to be interchangeable in position with each other, a fixed bracket wherein the frame is pivotally mounted, a hook or shoulder formed on the bracket, releasable means controlled by the rocking 60 of the frame about its pivot axis for locking the entrances in either of their reversed 65 positions, and a stop member movable at will into the path of said hook to arrest the frame and thus prevent unlocking of the 70 entrances when they are rocked downwardly for access to the magazines.

13. In a typographical distributing machine, the combination of two magazine entrances arranged in inverted relation to each other, a frame in which they are rotatably mounted for interchange, a fixed bracket wherein the frame is pivotally mounted, a hook or shoulder formed on the bracket, a hinged finger bar resiliently mounted on 80 said frame, and a pin or lug adapted by the depression of the yoke to engage the hook when the frame is swung downwardly for access to the magazines.

14. Typographical distributing mechanism including, in combination, two distributor bars movably mounted so as to be interchangeable in operative position with each other, and an indicator, operable automatically as the bars are interchanged, for designating the bar in use.

15. Typographical distributing mechanism including in combination, two upper matrix conveying screws arranged side by side in parallelism and a lower conveying 95 screw disposed beneath one of the upper screws, and two distributor bars arranged at right angles to each other, one of said bars being mounted for bodily rotation about the axis of one of the upper screws, and the other of said bars being mounted for bodily rotation about the axis of the other upper conveying screw.

16. Typographical distributing mechanism including in combination, a set of 105 matrix conveying screws, two distributor bars mounted independently of each other and movable for interchange in operative position with each other, and means connected to the two said distributor bars and 110 operable at will to effect their interchange.

In testimony whereof, I have affixed my signature hereto.

DAVID S. KENNEDY.
